US0D1041098S

(12) **United States Design Patent** (10) **Patent No.:** **US D1,041,098 S**
(45) **Date of Patent:** **** Sep. 3, 2024**

(54) **ANTI-BARK COLLAR**

(71) Applicant: **Shenzhen TIZE Technology Co., Ltd.**,
Guangdong (CN)

(72) Inventor: **Jian Wen**, Guangdong (CN)

(73) Assignee: **Shenzhen TIZE Technology Co., Ltd.**,
Guangdong (CN)

(**) Term: **15 Years**

(21) Appl. No.: **29/882,465**

(22) Filed: **Jan. 13, 2023**

(30) **Foreign Application Priority Data**

Dec. 9, 2022 (CN) 202230825188.9

(51) **LOC (14) Cl.** **30-99**

(52) **U.S. Cl.**

USPC **D30/199**

(58) **Field of Classification Search**

USPC D30/199, 144, 155, 151; D10/104.1,
D10/104.2

CPC .. A01K 15/021; A01K 15/022; A01K 15/029;
A01K 27/00; A01K 27/006; A01K 27/009

See application file for complete search history.

(57) **CLAIM**

The ornamental design for an anti-bark collar, as shown and described.

DESCRIPTION

FIG. 1 is a perspective view of an anti-bark collar, showing my design.

FIG. 2 is another perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines depict portions of the anti-bark collar that form no part of the claimed design.

1 Claim, 8 Drawing Sheets
